UNITED STATES PATENT OFFICE

94,635

DESIGN FOR A CLAW FOR WIRE STRETCHERS

John W. Schmitt, Pocahontas, Ill.

Application December 1, 1934, Serial No. 54,214

Term of patent 7 years

To all whom it may concern:

Be it known that I, John W. Schmitt, a citizen of the United States, residing at Pocahontas, in the county of Bond, and State of Illinois, have invented a new, original, and ornamental Design for a Claw for Wire Stretchers, of which the following is a specification, reference being had to

the accompanying drawing, forming part thereof.

The figure is a perspective view of a claw for wire stretchers showing my new design.

I claim:—

The ornamental design for a claw for wire stretchers, as shown.

JOHN W. SCHMITT.
